UNITED STATES PATENT OFFICE

136,343

DESIGN FOR A MIXING SPOON

Homer Gamache, Newark, N. J.

Application July 21, 1943, Serial No. 110,718

Term of patent 14 years

To all whom it may concern:

Be it known that I, Homer Gamache, a citizen of the United States, residing at Newark, in the county of Essex and State of New Jersey, have invented a new, original, and ornamental Design for a Mixing Spoon, of which the following is a specification, reference being had to the accompanying drawing, forming a part thereof.

In said drawing:

Fig. 1 is an obverse face view, Fig. 2 is a side edge view, and Fig. 3 is a transverse sectional view, taken on line 3—3 in Fig. 1 of a mixing spoon embodying my new design.

I claim:

The ornamental design for a mixing spoon, as shown,

HOMER GAMACHE.
